UNITED STATES PATENT OFFICE.

GEORGE CADDICK, OF ALLEGHENY, PENNSYLVANIA.

SOUNDING-BOARD FOR PIANOS.

SPECIFICATION forming part of Letters Patent No. 293,414, dated February 12, 1884.

Application filed February 20, 1882. (No model.)

To all whom it may concern:

Be it known that I, GEORGE CADDICK, of Allegheny, Pennsylvania, have invented certain new and useful Improvements in Sounding-Boards for Grand and Upright Pianos, of which the following is a specification, reference being had to the accompanying drawings.

The invention relates to upright pianos; and it consists in a double sound-board composed of back and belly sound-boards united at their side edges by walls and forming a sounding-chamber, said sound-boards being sprung into an arched or crowning form by means of sound-posts extending from the ribs of one sound-board to the other, said chamber having apertures or holes to emit the sound. This sound-chamber is covered with a full iron frame, which may be made to any desired scale and pattern.

The novelty consists in springing the belly sound-board and at the same time bowing the back sound-board by means of the posts introduced between them, thus producing two elastic sound-boards.

Figure 1 is a plan view of a device embodying my invention. Fig. 2 is a longitudinal section of the same. Figs. 3 and 4 represent, respectively, transverse and vertical sections of the two sound-boards arranged one on each side of the back framing of the piano.

A in the accompanying drawings is the back frame of the piano, constructed, in the usual way, to any desired pattern. To the inner side of the back frame one-inch pieces of board B C are glued to the top, sides, and bottom. On the one-inch pieces of board is glued the back sound-board, G, having previously been made the required thickness, (the fiber of both the sound-boards to run perpendicularly when placed in the instrument,) and provided with ribs M, placed at right angles to the fiber of the sound-board. The ribs are set at equal distances apart, so that the sound-posts, when glued onto the ribs of the back sound-board, will come immediately under the ribs of the belly sound-board, arranged either in rows or in a direct line beneath the bridges, (if in rows, it will take from sixteen to twenty sound-posts,) the sound-posts to be of such a height that when the belly sound-board H is sprung over them the back sound-board will bow about one-fourth of an inch in the center and leave

the belly sound-board sprung in the center also about one-fourth of an inch. The sound-posts around the outer edge of the sound-board should be about one-fourth of an inch higher than the space between the ribs of the two sound-boards, and the sound-post in the center about one-half inch higher than the space between the ribs of the two sound-boards, so that the sound-boards will bow evenly from the sides and ends to the center.

D and E are two planks, two and a half or three inches thick, equal to the width between the two sound-boards. These planks are glued to the inner side of the back sound-board, G. On the plank-piece D is glued the belly sound-board H and the wrest-plank J. The belly sound-board, being provided with bridges L, is sprung over the sound-posts for their equivalents, and then glued to the lower plank-piece, I. The bridge L is to be planed off in the middle, so that it will be level on the top and project above the plane of the full iron frame K enough to give a proper bearing to the strings and to sufficiently compress the belly sound-board—say about one-sixteenth of an inch.

The iron frame K may be made to suit any scale, and to any desired pattern, and is firmly put on over the sound-chamber formed by the sound-boards G and H. Where economy in space is required in the depth of the piano, the sound-boards may be put on each side of the back frame, leaving the back frame inside and between the back and belly sound-boards. According to this arrangement the back sound-board will be glued to a strip that is glued at the top, bottom, and sides, on the outside or back of the back frame. The sound-posts are glued in such places as will not come in contact or interfere with the back frame. The belly sound-board is then glued to the wrest-plank, which in turn is glued to the inner side or front of the back frame, after which the belly sound-board is sprung over the sound-posts and glued to the top, bottom, and sides of the back frame. The bridges are then fitted onto the belly sound-board and the iron frame put on, as previously described. A screw-press may be made that would spring the belly sound-board over the sound-posts and glue it down at the same time, thus facilitating the springing process. This arrangement of sound-boards—one on each side of the

back framing—may be applied to grand pianos. It is the most practicable way, and the upright piano so constructed will remain longer in tune. Figs. 3 and 4 in drawings represent, respectively, transverse and vertical sections of an upright-piano framing and sound-board arranged in this way. It will be remembered that the back sound-board is glued on flat, and is only bowed by the force employed in springing the belly sound-board over the sound-posts and by the pressure of the string on the bridges. At the time when the belly sound-board is about to be sprung over the sound-posts the tops of the sound-posts may be touched with glue, so that the sound-posts will be glued to the ribs of the belly sound-board, as well as to the ribs of the back sound-board, to prevent any rattle or jarring ever occurring.

20 To persons skilled in the art of piano-manufacturing I will explain my present mode of construction upon the theory of sound and its propagation. My improvement is the result of many experiments, including the construction of three experimental pianos.

Sound is produced by the vibration of elastic bodies. In many cases the elasticity of a body can be augmented by producing a closer aggregation of the molecules. Some metals are rendered more elastic by hammering them cold. Steel acquires a greater elasticity by tempering, and wood is rendered more elastic by the compression or distention of its fibers. In accordance with this theory, the object to be attained, then, is to put the sound-boards in a condition of elasticity and keep them so, which is done by springing the belly sound-board over the sound-posts, thus distending the fiber, while the fibers of the back sound-board are distended by the pressure brought to bear

on it by springing the belly sound-board over the sound-posts and by the pressure of the strings on the bridges. Heretofore in the construction of pianos with one sound-board the objection has been that the sound-board, being exposed to varying temperatures and atmospheres, has soon lost its curvature and elasticity, and hence arises the chief cause why pianos so soon depreciate in tone. In my double sound-board it has been my object 45 to preserve the curvature, elasticity, and sonorosity as long as possible. By this method of springing the sound-boards over sound-posts all pull-over from the wrest-plank is prevented, the back sound-board acting as a stay 50 or brace to it. The strings can take a more solid bearing on the bridges, as sinking of the sound-boards cannot occur, for the sound-boards support and re-enforce each other. 55

I am aware that pianos with double sound-boards connected by sound-posts are old, and such are not broadly claimed; but

What I claim, and desire to secure by Letters Patent as my invention, is—

In a piano, the double sound-board composed 65 of the two sound-boards, one in front of the back framing, the other in rear of it, said boards being sprung into an arched or crowning form by means of sound-posts introduced between them, substantially as specified. 70

In testimony that I claim the foregoing improvements in upright pianos, as above described, I have hereunto set my hand this 16th day of February, 1882.

GEORGE CADDICK.
